UNITED STATES PATENT OFFICE.

ABRAHAM HILLER, OF NEW ORLEANS, LOUISIANA.

DESIGN FOR A STOCKING.

Application filed February 13, 1928. Serial No. 25,427. Term of patent 14 years.

To all whom it may concern:

Be it known that I, ABRAHAM HILLER, a citizen of the United States, residing at the city of New Orleans, parish of Orleans, and State of Louisiana, have invented a new, original, and ornamental Design for Stocking, of which the following is a specification, reference being had to the accompanying drawing, forming part thereof.

The drawing is a rear elevation showing my new design of stocking.

I claim:

The ornamental design for a stocking, as shown.

ABRAHAM HILLER.
